UNITED STATES PATENT OFFICE.

ELIZABETH C. KNEIP, OF MASPETH, NEW YORK.

LANTERN.

1,388,267.

Specification of Letters Patent. Patented Aug. 23, 1921.

Application filed January 25, 1921. Serial No. 439,761.

To all whom it may concern:

Be it known that I, ELIZABETH C. KNEIP, a citizen of the United States, residing at Maspeth, in the county of Queens and State 5 of New York, have invented certain new and useful Improvements in Lanterns, of which the following is a specification.

My invention relates to lanterns, and more particularly to signal or warning lanterns 10 such as are used in some localities in cemeteries, and also by contractors for indicating the presence of excavations or obstructions.

The objects of my invention are to provide a lantern of this character which shall be weather proof and reliable, cheap to manufacture, and equipped with means by 15 which it may be readily anchored to the ground, so as to prevent accidental moving or upsetting such as now frequently occurs 20 with lanterns of the ordinary construction.

In order that my invention may be readily understood, reference is had to the accompanying drawings, forming part of this specification, and in which:—

25 Figure 1 is a side elevation of the lantern complete, parts being broken away;

Fig. 2 is a sectional plan view substantially on the line 2—2 of Fig. 1; and

30 Fig. 3 is a vertical central section substantially on the line 3—3 of Fig. 2.

My improved lantern consists of a base comprising a plate 1, and a cylindrical web or flange 2, preferably formed of thin sheet metal, and secured to the plate 1 at right 35 angles thereto. While I have shown this flange 2 as cylindrical, obviously it can be of any other desired shape. The plate 1 is shown as circular, and this is preferred, although, of course, it may be of other shapes.

40 Carried by the upper face of the plate 1 is an annular upstanding wall or guard 4 preferably serrated as shown and within this guard is held a chimney 5 preferably formed of clear transparent glass. This chimney is 45 open at its upper end as indicated at 11, and within the chimney and resting upon the plate 1 is the source of light. This preferably comprises a container 6 adapted to receive a short thick candle 7 having a central wick 8. It will be particularly noted 50 that the candle is of such dimensions that

the flame from the lighted wick lies within and below the top of the container 6. In other words, the container itself surrounds the flame. Preferably this container is 55 formed of colored glass, red being the usual color employed, and by this simple means the desired color is imparted to the light.

The lower edge of the chimney 5 rests upon the plate 1 with a substantially air 60 tight fit and openings 10 are provided in the upper part of the chimney 5 to supply air necessary to support combustion.

Above the chimney 5 is arranged a hood or canopy 14, preferably of conical shape as 65 shown and this is supported by a second guard member 12 having upwardly extending serrations 13 which are soldered or otherwise secured to the canopy.

The guard and canopy are supported by 70 means of a pair of rods 15 which extend downwardly through openings 16 in the base plate 1 and are adapted to be embedded in the ground on which the base rests.

Since in most cases where a lantern of this 75 character would be employed either the ground is soft, or there are piles of loose earth adjacent the excavation or the like, the presence of which is to be indicated, it is an easy matter to thrust the rods 15 into such 80 soft ground or loose earth as indicated in the drawings. Also, preferably, the lower comparatively sharp edge of the base flange 2 is likewise thrust into the ground to give additional stability to the lantern. It will be 85 obvious that by means of the base flange 2 and the rods 15, the lantern structure is effectively anchored and prevented from being accidentally overturned by the wind, or other causes.

90 It will, therefore, be seen that I have provided an efficient and reliable contractor's lantern which is cheap to manufacture and exceedingly simple to operate, and it is thought that the many advantages of my invention will be appreciated without further discussion.

95 What I claim is:

1. A lantern comprising a flat base plate 100 having a pair of openings, a member protruding downwardly therefrom and adapted to be thrust into the ground, a source of

light and a chimney supported by said base plate, and a pair of anchor rods, disposed one on each side of said chimney, passing through the openings in the base plate.

5 2. In a lantern of the character described, the combination with a base having an opening, of a source of light and a chimney supported on said base, a canopy or hood above

said chimney, and a rod supporting said canopy and passing through said opening, 10 said rod being extended below said base, and adapted to be embedded in the ground to serve as an anchor.

In testimony whereof I affix my signature.

ELIZABETH C. KNEIP.
